CHARLES FRASER, OF NEW YORK, N. Y.

Design No. 3,269, dated December 1, 1868.

DESIGN FOR A BRIDLE-FRONT, &c.

The Schedule referred to in these Letters Patent and making part of the same.

To all whom it may concern:

Be it known that I, CHARLES FRASER, of the city, county, and State of New York, have invented or produced a new and original Design for an Ornament to Bridle-Fronts, and also for the gag or check-rein runner of bridles; and I do hereby declare the following to be a full and exact description thereof.

To form my improved design, I take a strip of thin sheet-metal, one surface of which is polished, gilt, or plated, and corrugate it transversely of its length from end to end.

The strip should be of such a length that, when contracted by the corrugations, it will still be of sufficient length to cover the whole of the front piece or check-runner, for which it may be intended, except the loops or fastenings; and its width should likewise be adapted to that of the strap to which it is applied, so as to cover, or nearly so, its whole surface.

The corrugated strips may be attached to the leather in any convenient manner, but preferably by spurs soldered to the back of the metal, and passed through incisions in the strap and clasped on the back.

The effect produced by the reflection of the light by the bright surface of the metal, due to the varied angles of the corrugations, is very brilliant and striking, particularly in the sunlight, and gives an imposing effect to the bridle, when worn, and one which is attained at a small expense.

The metallic strips being corrugated transversely of their length, remain sufficiently flexible to bend freely with the strap.

The size or number of the corrugations is quite immaterial to the effect.

I claim, as my invention, the herein-described design as an ornament to bridles.

In witness whereof, I have hereunto signed my name, in the presence of two subscribing witnesses.
